UNITED STATES PATENT OFFICE

144,522

DESIGN FOR A FLASHLIGHT

Earl L. Schofield, Rockford, Ill., assignor to
Burgess Battery Company, Freeport, Ill., a cor-
poration of Delaware

Application March 8, 1945, Serial No. 118,342

Term of patent 14 years

(Cl. D48—24)

To all whom it may concern:

Be it known that I, Earl L. Schofield, a citizen of the United States, residing at Rockford, in the county of Winnebago and State of Illinois, have invented a new, original, and ornamental Design for a Flashlight, of which the following is a specification, reference being had to the accompanying drawing, forming part thereof.

Fig. 1 is a top view of a flashlight showing my new design;

Fig. 2 is a side view;

Fig. 3 is an end view of the left end, the remainder of the flashlight not being shown;

Fig. 4 is a view showing the cross-sectional shape of the casing at the line 4—4 of Figure 2; and

Fig. 5 is a right end view thereof.

The dominant features of my design reside in the portions shown in full lines.

I claim:

The ornamental design for a flashlight, as shown and described.

EARL L. SCHOFIELD.
